UNITED STATES PATENT OFFICE.

ARBLA E. WALLICK, OF YORK, PENNSYLVANIA.

DISPLAY BOX.

Application filed December 17, 1926. Serial No. 155,482.

This invention relates to a box for holding cigars or confections. The box is of peculiar shape, being wider at the front than at the rear side and adapted, when used for 5 cigars, to display cigars of tapering form in a fan-shaped group. Because of the peculiar form of the box, it is necessary to construct it in a manner differing from that of the ordinary cubical box, in order to give 10 it the same rigidity.

In carrying out the invention, I provide a back piece which is relatively thick, compared with the other parts of the box, and which is preferably convex on its inner side, 15 and I provide a front piece consisting of a thin strip which is considerably longer than the back piece and curved in the arc of a circle substantially concentric with the inner side of the back piece. The front and back 20 pieces are of the same height and are joined at their ends by end pieces consisting of thin strips which project above and below the front and back pieces. Top and bottom pieces are provided, both alike in form and 25 size, these pieces flaring from rear to front and adapted to rest against the front and back pieces and to fit closely within the projecting portions of the end pieces. The several parts, except the top piece, are nailed 30 together and the top piece is hinged to the back piece. The end pieces are at an obtuse angle to the back piece, and the latter is made relatively thick so that the nails passing 35 through the end pieces into the back piece will enter the latter for their full lengths.

In the accompanying drawing,

Fig. 1 is a top plan view of the box, the top piece or cover portion being partly 40 broken away;

Fig. 2 is a section on the line 2—2 of Fig. 1; and,

Fig. 3 is a section on the line 3—3 of Fig. 1.

Referring to the drawing, 1 represents the back piece of the box, which is relatively thick from front to rear and convex on its inner face 1^a. The front piece 2 is composed of a thin strip of material, considerably longer than the back piece and curved so that it is substantially concentric with the convex face of the back piece. The back and front pieces are joined by end pieces 3—3, which flare outwardly from the ends

of the former to the ends of the latter. 55 The ends of the back piece are beveled so that the end pieces fit flatly against them, and nails 4 are driven through each end piece into the back piece. These nails lie at an angle to the line adjoining the ends 60 of the back piece, but, owing to the thickness of the latter, the nails do not go through its forward side, as would be the case if the back piece were a thin strip of material, as found in the ordinary rectangular cigar box. 65

The top piece 5 and the bottom piece 6 are alike in form and size. The top piece has a straight rear edge 5^a, its end edges 5^b flare outwardly from the rear edge, and its forward edge 5^c is curved to correspond with 70 the curvature of the front piece 2 and lies flush with the outer face of the front piece. The top piece is hinged to the back piece by a fabric strip 7. The end pieces 3—3 project above and below the back and front 75 pieces and when the top piece is in closed position it rests upon the back and front pieces and its ends fit closely against the upward projections of the end pieces. The bottom piece 6 is nailed to the rear and front 80 pieces and its ends lie within the downwardly projecting parts of the end pieces and are secured thereto by nails 8, driven through the end pieces into the bottom piece. In the ordinary rectangular cigar box, the bottom 85 piece overlaps the end pieces, while the top piece fits between the end pieces. In the present invention, the top and bottom pieces are alike and interchangeable, which effects an economy in manufacturing and assembling the box parts. 90

The box is suitable for containing and displaying confections and cigars. When used for the latter purpose, and with cigars which are wider toward their tip ends than 95 their butt ends, the convex face of the back piece holds the cigars in position against the arcuate front piece and the cigars are displayed in a fan-shaped series.

What I claim is:

1. A cigar box comprising a relatively thick back piece having beveled ends, an arcuate front piece, relatively long with respect to the back piece, straight end pieces secured to the ends of the back and front pieces, and top and bottom pieces having straight side edges flaring from the back to the front piece said top and bottom fitting 105

within said end pieces, the forward edges of said top and bottom pieces being curved to conform to the curvature of said front piece.

5 2. A cigar box comprising a relatively thick back piece, convex on its inner side and straight on its outer side a front piece substantially concentric with said inner side and relatively long with respect to the back piece, straight end pieces secured to the ends of said front and back pieces and project-

ing above and below the same, and flaring top and bottom pieces having straight side edges, said top and bottom pieces fitting within the projecting portions of the end pieces and lying against said front and back pieces, said top piece being hinged to the back piece. 15

In testimony whereof I hereunto affix my signature.

ARBIA E. WALLICK.
